UNITED STATES PATENT OFFICE.

JAMES W. COBURN, OF DETROIT, MICHIGAN.

VEHICLE-WHEEL.

1,128,760.

Specification of Letters Patent. Patented Feb. 16, 1915.

Application filed April 23, 1914. Serial No. 834,893.

To all whom it may concern:

Be it known that I, JAMES W. COBURN, a citizen of the United States, residing at Detroit, in the county of Wayne and State 5 of Michigan, have invented certain new and useful Improvements in Vehicle-Wheels, of which the following is a specification.

My invention relates to new and useful improvements in vehicle wheels and has for 10 one of its objects to provide an extremely useful and durable wheel for farm wagons, motor trucks and other heavy vehicles which consists of a plurality of wooden segments that are secured in a novel manner to provide a wheel, said segments being cut lengthwise of the grain to prevent shrinkage and cracking.

Another important object of my invention is to provide a wheel of the character described that consists of a plurality of wooden segments secured together in a novel manner, each of said segments being grooved upon its outer face so that when the segments are fitted together a continuous circumferential groove is provided and forms 25 double tread portions.

Another important object of my invention is to provide a wheel of the character described comprising wooden segments that 30 are formed to present the appearance of spokes.

My invention further contemplates generally improving vehicle wheels so as to render them more durable, practical, efficient and inexpensive to manufacture.

The above and additional objects are accomplished by such means as are illustrated in the accompanying drawings, described in the following specification and then more 40 particularly pointed out as claimed.

With reference to the drawings, wherein I have illustrated the preferred embodiment of my invention as it is reduced to practice, and throughout the several views of which 45 similar reference numerals designate corresponding parts, Figure 1 is a rear elevation of my improved wheel partly broken away to show some of the segments, Fig. 2 is a vertical sectional view taken through my improved wheel, Fig. 3 is a fragmentary front elevation showing the peculiar formation of the segments to represent spokes,

Fig. 4 is a detail perspective view of one of the segments, and Fig. 5 is a fragmentary elevation of an anti-skidding attachment for 55 my improved wheel.

Referring to the drawings by characters of reference, the numeral 1 designates a cylindrical tapered hub and 2 a circular plate formed integral with the inner end of the 60 hub 1. The plate 2 is provided with an inwardly extending circular flange 3 upon which is mounted a toothed gear ring 4 to coöperate with the driving mechanism of the vehicle, not shown. Mounted upon the 65 cylindrical tapered hub 1 and extending radially therefrom are a plurality of wooden segments 5. These segments 5 are formed of some suitable hard wood cut lengthwise of the grain and preferably chemically treated. 70 Each of the segments 5 is provided centrally of its end edges and upon its outer end with a groove 6, which when the segments are fitted together form a continuous circumferential groove and divide the segments into double tread portions 7 and 8. The outer surfaces of the segments are curved slightly so as to provide a comparatively even tread surface.

As a means for securely locking the segments in rigid engagement with each other so that lateral movement relative to each other is prevented I provide longitudinal grooves 9 and tongues 10 upon opposite sides of each segment. The tongues 10 fitting 85 with the grooves 9 thus providing a rigid joint.

Formed in the outer end faces of the segments intermediate the inner and outer edges thereof are inwardly extending transverse 90 recesses 11. The recesses 11 align, when the segments are placed in position and form continuous circumferential grooves, upon the inner and outer sides of the wheel. Metal bands 12 are shrunk within the recesses 11 95 in the ordinary manner and as will be clearly seen with particular reference to Fig. 2 in the drawings a space is provided between the outer surface of the bands and the upper walls of the recesses 11. Into this space I 100 pour molten brim stone or some other suitable material 13 and allow said material to harden to act as a binder and provide a rigid structure. The band upon the outer

face of the wheel projects outwardly from the wheel and acts as a shelf to support a ring 14 which rests in engagement at its inner edge upon the extended portion of said band and is secured by bolts or other suitable fastening means 15 to the outer end faces of the segments. The bolts 15 are inserted through counter-bored openings 16 formed adjacent the periphery of the plate 2, the segments 5, counter-bored openings in the ring 14 and have nuts 17 turned upon their unheaded terminals. The heads of the bolts lie within the counter-bored openings 16. The bolts in passing through the segments provide great rigidity for the structure. The outer edge of the ring 14 is spaced from the outer tread surface of the wheel the same distance as is the periphery of the plate 2.

20 The inner ends of the segments 5 are curved and slightly inclined as at 18 to conform to the shape of the hub 1.

In order to have the outer faces of the segments represent spokes I cut the outer face of each segment inwardly toward the smaller end from the inner edge of the recess 11, then chamfer the edges of the cut end portion as at 19 for a distance equal to more than half of the cut end portion. 25 This arrangement provides a slightly projecting portion 20 which presents the appearance of a spoke.

Mounted upon the outer end of the hub 1 is a circular plate 21 that is apertured centrally to receive the hub 1 and extends at right angles thereto. The plate rests against the inner unchamfered portions 22 of the segments as shown in Fig. 2 and is provided adjacent its periphery with counter-bored 30 openings 23 arranged circumferentially of the plate in slightly spaced relation to each other. At points opposite the openings 23 I provide similar openings 24 in the plate 2. The bolts 25 similar to the ones 15 are inserted through the openings 24, the segments 5 have their unheaded and threaded terminals disposed within the openings 23 and have nuts 26 turned thereon. A suitable hub cap 27 is turned upon the outer end of the hub 18. The bolts 15 and 25 are arranged adjacent the inner and outer ends of the segments and in extending through the segments and being secured provide rigidity and strength for the wall so that possibility 35 of accidental derangement of the segments is eliminated.

As shown in Figs. 2 and 5 I provide an anti-skid attachment for my improved wheel which consists of an annular ring 28 which 40 is approximately L-shaped in cross section and upon its periphery is provided with a plurality of spaced and preferably pointed projections 29 which are designed to grip the road surface and prevents skidding.

65 To enable the securing of the attachment,

I provide a plurality of inwardly extending securing plates 30 that are provided with apertured inner ends 31 and are approximately L-shaped to conform to the shape of the ring 28. The plates 30 are secured by 70 suitable fastening means 32 at spaced points upon the ring 28 and are so arranged that the bolts 15 may be utilized to secure the attachment. The ring 28 is to be secured upon the outer face of the wheel so that the 75 projections 29 extend their full length beyond the tread surface of the wheel as shown in Fig. 2. I provide a plurality of radially supporting arms 32 that are secured at their ends to the ring 28 and an 80 inner ring 33. The inner ring 33 is designed to fit upon the hub cap 27 as shown in Fig. 2 in the drawings.

It will be readily seen that the anti-skid 85 may be easily and readily secured to the wheel and will positively prevent skidding.

With reference to the foregoing description and accompanying drawings it will be noted that I have provided an extremely useful and durable wheel which will be of great service in connection with heavy farm vehicles and motor trucks for reason of its 90 rigidity, durability, efficiency and cheapness.

In practice, I have found that the form 95 of my invention, illustrated in the drawings and referred to in the above description, as the preferred embodiment, is the most efficient and practical; yet realizing that the conditions concurrent with the adoption of 100 my device will necessarily vary, I desire to emphasize the fact that various minor changes in details of construction, proportion and arrangement of parts may be resorted to, when required, without sacrificing 105 any of the advantages of my invention, as set forth.

What is claimed is:—

1. A wheel comprising a hub, a plurality 110 of segments secured upon the hub and having grooves in their outer faces, an annular band mounted within said grooves, said band extending outwardly from said adjacent face of the wheel, a plate carried by the hub and engaging upon the inner faces of the segments, an annular band mounted upon the outer faces of the segments and engaging upon its inner edge the normally projecting portion of the first annular band and bolts inserted through the last named annular 115 band, segments and plate carried by the hub.

2. A vehicle wheel comprising a hub, a plate carried upon the inner end of the hub, a plurality of segments mounted upon the hub and engaging upon their inner faces 120 said plate, each of said segments having a groove formed in the outer face thereof, said grooves alining with one another, a band mounted within the grooves and projecting from the outer faces of the segments, an 125 an-

annular band mounted upon the outer faces of the segments and engaging upon its inner edge the projecting portion of the first annular band and fastening elements inserted 5 transversely through each of the segments and being secured to the second annular band and plate.

In testimony whereof I affix my signature in presence of two witnesses.

JAMES W. COBURN.
